DESIGN.

—o—
W. McCALLUM.

CARPET.

No. 17,946.

Patented Dec. 13, 1887.

UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,946, dated December 13, 1887.

Application filed November 14, 1887. Serial No. 255,159. Term of patent 3½ years.

To all whom it may concern:

Be it known that I, WILLIAM McCALLUM, of Yonkers, in the county of Westchester and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design comprises a body portion, A, and a border, B. The body portion A is a mass of conventionalized flower and leaf forms closely and irregularly grouped together, as is clearly shown in the accompanying photograph.

There are several large circular flower figures somewhat prominent in this body portion, and several broad leaf figures and a group of web-

like leaf figures and a pomegranate group. Many smaller groups and figures fill the design 25 closely. The border portion B shows the same large flower and leaf figures massed together, with similar groups of small figures filling closely the interstices and with a mass of circular radial figures as the base of the border 30 portion.

The photograph clearly shows all the details of the design.

What I claim as new, and desire to secure by Letters Patent, is—

1. The design for carpets, consisting of the body portion A, substantially as shown.
2. The design for carpets, consisting of the border portion B, substantially as shown.
3. The design for carpets, consisting of the 40 body portion A and the border portion B, substantially as shown.

WILLIAM McCALLUM.
